UNITED STATES PATENT OFFICE

2,508,193

RECLOSABLE CARTON

William A. Ringler, Wayne, Pa., assignor to The Gardner Board and Carton Co., a corporation of Ohio

Application February 23, 1946, Serial No. 649,623

7 Claims. (Cl. 229—17)

1

It is an object of my invention to provide a carton having means for ready opening, which carton is reclosable in the sense not only of having a portion for the closure of the opening formed therein, but also having means for positively retaining the closure in closed position.

It is an object of my invention to provide a carton having these advantages which nevertheless, as produced by the carton manufacturer and as used by the packager of materials, is in the form of the familiar seal-end carton, is capable of being closed or sealed with as tight a closure initially, is capable of rendering the same protection of goods in transit or storage, and requires no extra operations in manufacture, filling and closing.

These and other objects of my invention which will be set forth hereinafter, or will be apparent to one skilled in the art upon reading these specifications, I accomplish by that structure and arrangement of parts of which I shall now disclose an exemplary embodiment. This embodiment is illustrated in the accompanying drawings, wherein:

Figure 1 is a plan view of the blank for producing the carton of my exemplary embodiment.

Figure 2 is a plan view of the tubed blank or carton in knocked down condition.

Figure 3 is a perspective view of the opened carton.

Figure 4 is a perspective view of the carton in reclosed condition.

In the exemplary embodiment I provide a carton having enclosing body walls 1, 2, 3 and 4, and a glue flap 5 articulated together by the usual score lines. The body walls are provided with seal-end flaps 6, 7, 8 and 9, at one end, and their primed counterparts at the other end. The score line articulating the seal-end flaps 6 to 8 to the respective body walls, is indicated at 10. A similar score line articulates the flaps to the body walls at the other end of the carton.

The flap 7 is provided with an intermediate score line 11, and the flap 9 is provided with a line of weakening 12, these lines being so placed in the several flaps as to come into coincidence when the flaps are folded in the operation of closing the carton.

A line of weakening 13 extends diagonally downwardly in the body wall 2, from the end of the score line 11 in the flap 7. A similar line of weakening 14 extends diagonally in the opposite direction in the body wall 4, from the end of the line of weakening 12 in the flap 9. A line of weakening 15 extends across the body wall 1, at the end of the line of weakening 13,

2

and parallel to the score line 10. The glue flap 5 is weakened or preferably cut across as at 16, at the same level as the line of weakening 15. This forms a tab 17 at the end of the glue flap.

The glue flap is provided with an extension 18 of substantial length articulated to it along a score line 19. At the level of the cut line 16 I transversely score this extension as at 20, so that at the upper end of the extension there is a portion 21 at the level of the tab 17, but severed from it as shown. The extension 18 is carried above the level of the score line 10 to form a preferably rounded tab 22, demarcated from the portion 21 by a transverse score line 23. The closure flap 9 is cut away as at 24 in an area similar in shape to the tab 22.

The carton blank illustrated in Figure 1 may be handled and tubed in the usual fashion and on the usual carton tubing mechanism. Suitable adhesive is applied by a glue stiper or equivalent mechanism, to the glue flap 5 including its tab 17, no adhesive being applied however, to the glue flap extension 18. Then the carton is tubed by being folded first along the line of articulation between body walls 3 and 4, and next along the line of articulation between body walls 1 and 2. This folding, and the ensuing pressing results in the adherence of the glue flap 5 to the under side or inside of the free edge of body wall 1, giving the tubed structure illustrated in Figure 2.

This structure is in form a seal-end carton which may be erected, closed on one end, filled and closed on the other in the ways hitherto current in the art, and without change in either process or mechanism. Either end of the carton may, if desired, be sealed over a mandrel as is the usual practice for the first closure; and the second closure may be formed on either end of the carton. In closing and adhesively securing those flaps which have been illustrated at the upper end of the blank in Figure 1, it will be understood that flaps 6 and 8 are those first folded, and that flap 9 is the intermediate flap over which flap 7, as the final or outside flap, is folded. The glue flap extension 18 lies within the carton and in the closed package is concealed from view. The act of folding over the flap 6 under which the tab 22 lies, will result in this tab being folded. It will be understood that parts, 18, 21 and 22 are not adhesively secured.

The carton, in the hands of the ultimate consumer, may readily be opened by fracturing the body walls 1, 2 and 4 along the weakened lines 13, 14 and 15, whereupon a portion of the top of the carton may be raised as a lid, as illus-

trated in Figure 3. The score line 11 in flap 7 serves as a hinge for this lid; and the weakened line 12 in flap 9 enables this flap to break, as may be required for easy opening. The top panel of the lid structure is formed of flap 6 and portions of flaps 7 and 9, as will be clear. The tab 17 remains in adhesive union with the upper portion of the body wall 1, so that the top structure has integrated side and front walls formed essentially of portions of body walls 1, 2 and 4. When the carton is opened, portions 21 and 22 of the glue flap extension will project upwardly as shown in Figure 3. A portion of the contents of the carton may now be dispensed.

The carton may now be reclosed for the protection of the remainder of its contents by swinging the lid downwardly. In doing this the portions 21 and 22 of the glue flap extension are brought outwardly of the carton. The lid may be locked in closed position by inserting the tab 22 in the recess between flaps 6 and 7, formed by the cut-out 24 in the intermediate flap. The carton is shown in Figure 4 in reclosed and locked condition.

To increase the flexibility of the upper end of the glue flap extension, I may form as at 25, a slit at the upper end of the score line 19.

Modifications may be made in my invention without departing from the spirit of it. It will be understood that the size and shape of the carton itself form no limitation upon the exemplary embodiment. While I have shown a carton with seal-end flaps at both ends, it will be understood that a different closure may be employed upon one of the ends if desired. My construction may be embodied in cartons having any of the features ordinarily employed with seal-end structures without interference therewith. The size of the lid portion is likewise not a limitation. Since by configuring and placing the weakened lines 13 and 14, the size of the lid may be varied as desired, even to the extent of causing the entire top of the carton to form a lid hinging upon a score line at the upper end of or within the body wall 3; but it is usually preferred that the lid, per se, be small in area since such lids form tighter closures upon reclosing.

Having thus described my invention in an exemplary embodiment, what I claim as new and desire to secure by Letters Patent is:

1. A blank for a carton of the class described comprising enclosing body walls and a glue flap in articulation forming a structure capable of being tubed, seal-end flaps on the ends of said enclosing walls, and an extension on said glue flap providing a portion capable of projecting above the tops of the said enclosing walls, contiguous ones of said enclosing walls having lines of weakening therein on which said walls may be broken to form a lid for opening the carton, said glue flap extension being located at a place of opening, normally lying within the closed carton but being capable of swinging outwardly to come outside the said lid upon reclosure thereof.

2. A blank for a carton of the class described comprising enclosing body walls and a glue flap in articulation forming a structure capable of being tubed, seal-end flaps on the ends of said enclosing walls, and an extension on said glue flap providing a portion capable of projecting above the tops of the said enclosing walls, contiguous ones of said enclosing walls having lines of weakening therein on which said walls may be broken to form a lid for opening the carton, said glue flap extension being located at a place

of opening, normally lying within the closed carton but being capable of swinging outwardly to come outside the said lid upon reclosure thereof, an intermediate one of said seal-end flaps having an end lying contiguous to said glue flap cut away to provide in the closed carton a recess for accepting a projecting end portion of said glue flap extension.

3. A blank for a carton of the class described comprising enclosing body walls and a glue flap in articulation forming a structure capable of being tubed, seal-end flaps on the ends of said enclosing walls, and an extension on said glue flap providing a portion capable of projecting above the tops of the said enclosing walls, contiguous ones of said enclosing walls having lines of weakening therein on which said walls may be broken to form a lid for opening the carton, said glue flap extension being located at a place of opening, normally lying within the closed carton but being capable of swinging outwardly to come outside the said lid upon reclosure thereof, an intermediate one of said seal-end flaps having an end lying contiguous to said glue flap cut away to provide in the closed carton a recess for accepting a projecting end portion of said glue flap extension, said glue flap being severed to provide a tab which is free at the level of one of said lines of weakening.

4. In a carton, a plurality of body walls and a glue flap in articulation and forming a tubed structure in which said glue flap is adhered to one of said body walls, seal-end flaps on said body walls capable of being interfolded and adhesively secured to form a closure for the carton, a plurality of contiguous walls of said carton including the one to which said glue flap is attached, having lines of weakening whereby these walls may be severed to form an openable lid, said glue flap having an extension with a portion capable of projecting above the ends of said body walls, said glue flap also having a severed tab in the area of said lid, said tab being adhesively secured to a severable portion of a body wall, whereby to integrate side walls of said lid, an intermediate one of said closure flaps having a recess to accept an end of said glue flap extension for locking purposes.

5. A carton including a blank cut and scored to provide a tubular body with enclosing body walls and closure flaps, said carton having lines of weakening in contiguous body walls thereof upon which said body walls may be broken to provide a hinged lid raisable to open the carton, and a strap-like member affixed to one of said contiguous walls below the line of weakening therein and of a length to extend beyond the top of the wall, said strap-like member having an end portion adapted to be bent into the plane of the top of said carton as formed by said closure flaps, said strap-like member being formed as part at least of a flap integral with said blank and folded against the said body wall to which said strap-like member is affixed.

6. A carton including a blank cut and scored to provide a tubular body with enclosing body walls and closure flaps, said carton having lines of weakening in contiguous body walls thereof upon which said body walls may be broken to provide a hinged lid raisable to open the carton, and a strap-like member affixed to one of said contiguous walls below the line of weakening therein and of a length to extend beyond the top of the wall, said strap-like member having

an end portion adapted to be bent into the plane of the top of said carton as formed by said closure flaps, an intermediate one of said closure flaps having an edge lying along the top of the contiguous body wall to which said strap-like member is affixed, which is cut away to form, with adjacent flaps, a slot into which said end portion of said strap-like member may be inserted to hold said carton closed.

7. The structure claimed in claim 6 wherein said lid is hinged at the top of the carton along a line transverse certain closure flaps thereof.
